Primary Examiner — Marianne Pandozzi

CLAIM

The ornamental design for a coffee maker, as shown and described.

DESCRIPTION

FIG. 1 is a front view of the coffee maker;
 FIG. 2 is a left side view of the coffee maker;
 FIG. 3 is a right side view of the coffee maker;
 FIG. 4 is a rear view of the coffee maker;
 FIG. 5 is a top view of the coffee maker;
 FIG. 6 is a bottom view of the coffee maker; and,
 FIG. 7 is a perspective view of the coffee maker.
 The broken lines are for illustrative purposes only and form no part of the claimed design.
